UNITED STATES PATENT OFFICE.

HINSDALE SMITH AND ARTHUR P. SMITH, OF SPRINGFIELD, MASSACHUSETTS.

METAL VEHICLE-BODY.

No. 813,460.

Specification of Letters Patent.

Patented Feb. 27, 1906.

Application filed May 22, 1905. Serial No. 261,707.

To all whom it may concern:

Be it known that we, HINSDALE SMITH and ARTHUR P. SMITH, citizens of the United States of America, residing at Springfield, in the county of Hampden and State of Massachusetts, have invented new and useful Improvements in Metal Vehicle-Bodies, of which the following is a specification.

This invention relates to an improved metal vehicle-body possessing special utility in connection with the manufacture of vehicles of the automobile type.

To this end the invention contemplates certain structural improvements in metal-body constructions for vehicles which provide for greatly lessening the weight of the body without impairing its strength or rigidity, while at the same time securing a construction and arrangement of parts which greatly facilitates the assembling of the several component members of the structure and also permits of an advantageous disposition of rivets.

It is well known that one of the principal difficulties experienced in the construction of motor-vehicles is that of the great weight of the body of the vehicle, and it has been the constant aim to lessen such weight without affecting the general rigidity and strength of the body structure. Where this has been attempted in sheet-metal bodies, no material reduction in weight has been secured, for the reason that in these sheet-metal constructions the thin edges of each plate or piece has usually been reinforced by a strip of angle-iron, which greatly adds to the weight of the body. Furthermore, in the employment of angle-iron reinforce for the thin edges of sheet-metal plates the heads of the rivets are necessarily left exposed on the outside of the thin metal of the body, and this thin material will always work away from the more rigid angle-iron, with the result of causing the varnish or paint to crack, and thus outline the head of the rivet through the finish or in the finish material.

It is therefore one of the special objects of the present invention to overcome the disadvantages of using angle-iron reinforcing-strips by providing a construction which permits the elimination of angle-iron reinforces in nearly all places throughout the body structure, thereby saving from seventy-five to one hundred pounds in the weight of the body. While accomplishing this desirable result, the

improved construction is quite as stiff and 55 rigid as that reinforced with angle-iron and at the same time possessing the further distinct advantage that there are no exposed rivet-heads on the outside of the body. In this particular the improvements contemplated by the present invention provide for the material lessening of the weight of the body structure without sacrificing strength or rigidity.

Another object of the invention is to provide an improved reinforced metal bridge construction beneath the front edges of the seats and likewise an improved reinforced door and door-jamb construction embodying the salient features of the general body construction to carry out the general purpose and design of the invention.

Other objects and advantages of the invention will hereinafter appear, and the latter consists of the novel construction, combination, and arrangement of parts described, illustrated, and claimed.

The essential features of the invention embodied in the structural improvements for carrying out the above objects are necessarily susceptible to modification without departing from the general scope of the invention; but a preferred embodiment thereof is shown in the accompanying drawings, in which—

Figure 1 is a general skeleton perspective view of a metal vehicle-body embodying the improvements contemplated by the present invention. Fig. 2 is an enlarged sectional perspective view of the door and door-jamb construction. Fig. 3 is a detail cross-sectional view on the line 3 3 of Fig. 2, illustrating the door-jamb reinforce-strip, so located as to bring its outer edge flush with the outer side of the body to receive the impact of the closing movement of the door, and thereby protect the metal sheet. Fig. 4 is a view similar to Fig. 3, showing a modification of the arrangement of the door-jamb reinforce. Fig. 5 is a perspective sectional view on the line 5 5 of Fig. 1, illustrating the reinforced metal bridge construction for the front of the seats. Fig. 6 is a perspective sectional view of one of the rear corners of the body. Figs. 7 and 8 are horizontal sectional views, respectively, on the lines 7 7 and 8 8 of Fig. 6. Fig. 9 is a vertical sectional view on the line 9 9 of Fig. 6, the direction of the view being indi-

cated by the arrow. Fig. 10 is an enlarged vertical sectional view of a side wall of the body, the plane of section being on the line 10 10 of Fig. 1 and illustrating the interior 5 stiffening-frames usually employed at this part of the body. Fig. 11 is a detail sectional view illustrating the construction of the side entrance door-sill and showing the application of the reinforcing-strip and also illustrating the reinforcement of the metal body 10 below the sill.

Like reference characters designate corresponding parts in the several figures of the drawings.

15 In carrying out the invention one of the objects thereof is to adapt the structural improvements in metal-body construction to any form or type of vehicle-body; so no special change is contemplated in the general 20 outline or configuration of any particular kind of vehicle-body constructed in accordance with the invention. Hence, for illustrative purposes, these improvements are shown in the drawings as adapted to the construction of a sheet-metal body of a conventional form, such as employed in motor-ve- 25 hicles.

As indicated in the statement of objects, a distinctive feature of the present invention 30 resides in constructing the metal plates forming the body and seats in such a way as to permit the elimination of the usual angle-iron reinforces in nearly all places. Referring particularly to this phase of the invention, 35 the numeral 1 in the drawings designates the sheet-metal body-plates of the body proper, which plates preserve the conventional configuration of the vehicle-body and occupy the usual relative positions. In the form of 40 motor-vehicle body shown in the drawings in this application the said body-plates 1 are arranged to form the opposite side walls of the body proper and also the transverse body members united to the side walls to provide 45 the necessary transverse bracing, as well as for the proper support of the seats surmounting the body proper.

Instead of reinforcing the borders or marginal edges of the sheet-metal plates 1 with 50 angle-iron reinforce-strips, as heretofore commonly resorted to, the present invention contemplates forming the metal plates of the body proper along their borders or marginal edges with the continuous inturned stiffening-flanges 2, projecting inwardly from the vertical planes of the body-plates. The in-turned stiffening-flanges 2 are preferably integral with the body-plates, from which they are projected inwardly and bent to the plane 55 indicated to provide body-plates which are quite as stiff along their marginal edges or borders as plates reinforced with angle-iron strips, while at the same time providing a further distinct advantage of dispensing with 60 the outer exposed rivet-heads, which are nec-

essarily employed in connection with thin metal plates reinforced at their borders by stouter and more rigid angle-iron strips, the objections to which latter construction have already been pointed out.

70 While the inturned marginal flanges 2 of the sheet-metal body-plates provide for a stiffening and reinforcing of the marginal borders of such plates, the present invention contemplates an additional reinforcement at this 75 point by forming the plates contiguous to the said marginal flanges 2 with the broad outwardly-convexed reinforce-beads 3. The reinforce-beads of each sheet-metal body-plate are of a concavo-convex shape in cross-sec- 80 tion, the same being stamped directly in the sheet-metal plate and paralleling the marginal stiffening-flanges 2 in directly contiguous relation thereto, thus combining with such flanges to produce an exceptionally strong 85 and rigid marginal construction for the body-plates. At the same time the upper of said inturned marginal stiffening-flanges 2 of the upright body-plates present flat horizontal bases, upon which the superstructure of the 90 vehicle-body can be placed and secured with the greatest facility. This marginal or border formation of the sheet-metal body-plates is preserved throughout the entire body construction as far as practicable, thus securing 95 a stiffening and reinforcing effect throughout, which serves to maintain the rigidity and strength of the body, while at the same time providing for materially lightening the same.

At the corners of the body or at the points 100 where a side wall and transverse body member make a right-angle turn in the body construction and are to be united at their meeting-points the meeting ends of the corresponding marginal stiffening-flanges 2 are arranged 105 in overlapping relation, as plainly illustrated in detail Fig. 6 of the drawings. To provide for maintaining the upper rest-surfaces of the overlapping flanges 2 at the corners in the same plane, one of such flanges is preferably 110 depressed or offset, as indicated at 4, to provide a seat for receiving therein the corresponding end of the other of said flanges. A similar construction is preserved where the edges of the separate sheet-metal body-plates 115 are to be united, as plainly shown in Figs. 6, 7, and 8 of the drawings, in which figures the edges of the separate body-plates at the corner are shown arranged in overlapping relation with one of the overlapped plate edges, 120 formed with a depressed seat or offset 5, receiving the corresponding edge of the other plate and which overlapping edges are permanently secured together through the medium of the ordinary securing-rivets 6. Another feature of the corner construction 125 (shown in Figs. 6, 7, and 8 of the drawings) resides in the employment of a corner-reinforce plate 7. This corner-reinforce plate 7 is of triangular form, so as to register in the 130

corner-joint of the body beneath the overlapping ends of the marginal flanges 2 of the separate plates. Said flanges and said corner-reinforce plate 7 are permanently connected 5 by securing-rivets 8, passing through said flanges and also through the plate, thus completing an exceptionally rigid and strong corner-joint construction, as may be plainly seen from detail Figs. 6 and 9 of the drawings, the latter figure further illustrating the position of the corner-reinforce plate. In further connection with the corner construction just described, and illustrated in Figs. 6 to 9, inclusive, of the drawings, it will be 10 noted that when it is desirable to finish the corner on a curve, as indicated by the bracket and reference-numeral 9 on Figs. 7 and 8 of the drawings, the convexed reinforce-beads 3 of the separate united body-plates will not 15 merge in such a manner as to permit securing them together properly. Hence the said bead 3 on one of the plates is terminated short of the joint, as indicated by the reference-number 10 in Figs. 6 and 8 of the drawings, and an extra convexed or half-round 20 finishing-strip 11 is secured on the outer side of the lapping edge of one of the body-plates by means of the securing-rivets 6, previously referred to. This extra finishing-strip 11 25 takes the place of the vertically-disposed beading, which should be formed along this edge of the plate, and by presenting a rounded outer surface merging into the rounded corresponding surface of the adjacent vertical 30 bead 3 (see Figs. 7 and 8) provides a nicely-rounded corner for the body. The said strip 11 is preferably of brass and will necessarily have the heads of the rivets exposed; but where rivets are put through relatively thick 35 metal the heads will not work loose in the same manner as hereinbefore referred to. In connection with the rounded-corner construction just referred to it will of course be understood that the extra finishing-strips 11 are 40 used only on the two perpendicular rear corners of the body.

It will of course be understood in order to get the proper bracing or trussing effect, as well as to provide for supporting the different parts of the vehicle, there may be associated with the metal body-plates any suitable framework or braces. These expedients may be resorted to at the option of the manufacturer; but preferably in carrying out the 45 invention it will be found advantageous to provide specially for stiffening and bracing the front side wall extensions 12, which project forwardly from the front seats. The preferable construction employed for that 50 purpose is plainly shown in Figs. 1 and 10 of the drawings and consists in arranging within the inner side of each of said front extensions 12 an inner filling-board 13, preferably secured at its upper edge beneath and to the 55 upper inwardly-projecting marginal flange 2

by means of the fastening-screws 14 and having its lower edge resting on top of and secured to a lower horizontal supporting-strip 15^a, arranged on top of the lower marginal flange 2 and held in place through the medium of the fastening-screws 15, passing through said flange, said screws also engaging in the bottom edge of the filling-board 13, thus firmly uniting these several parts and holding them within the hollow or recessed inner side of the side wall extension. The lower horizontal supporting-strip 15^a, arranged on the bottom flange of each front side wall extension, is wider than the filling-boards 13 thereabove to provide an inwardly-projecting ledge or shelf 16, upon which is supported the ends of the floor-board 17, as plainly shown in detail Fig. 10 of the drawings. This construction may be carried throughout the body-plates constituting the 85 side walls of the body proper to not only provide the requisite stiffness against the vertical or horizontal strains, but also to provide a support for the floor-boards throughout.

In the adaptation of the invention illustrated in Fig. 1 of the drawings to a vehicle-body of the automobile type, said body is illustrated as being provided with a plurality of transverse body members, which may be designated by the reference character T, arranged in parallelism and one in advance of the other to secure the necessary cross-bracing for the body. The type of vehicle-body illustrated embodies a pair of individual front seats 18 and 18^a, arranged upon the front transverse seat-support provided therefor, and a single large rear seat 19 of a length equal to the full width of the vehicle-body and arranged upon the seat-support provided therefor, said rear seat 19 maintaining the usual spaced relation to the front seats 18 and 18^a, disposed in advance thereof. The separate individual front seats 18 and 18^a and also the single large seat 19 in rear thereof are constructed from sheet-metal bodies 20, shaped to the conventional or desired configuration of the seat and provided at their marginal edges or borders with continuous inturned stiffening-flanges 21 and directly contiguous to such flanges with the continuous outwardly-bowed concavo-convex reinforce-beads 22. Said elements 21 and 22 of the sheet-metal seat-bodies preserve the same relation and the same function as the corresponding elements 2 and 3 of the sheet-metal plates of the body proper, thus maintaining this stiffening or reinforcing feature of the metal plates throughout the entire body and seat structure. The sheet-metal bodies 20 of the front and rear seats are designed to be covered or upholstered in any approved way without affecting the present invention. The said seat-bodies have arranged within the bottom portions thereof the wooden or equivalent seat-

frames 23, which are suitably held in position upon the transverse seat-supports of the body proper. The transverse seat-supports for the front and rear seats are preferably of the same general nature, so a description of one will suffice for the other. Each of these seat-supports essentially consists of the opposite side walls of the body and a transversely - arranged metal bridge 24. This metal bridge 24 extends across the vehicle-body from one side wall to the other and essentially comprises a horizontal portion 25, underlying the front edge of the seat frame or frames and the opposite end legs 26, depending from the ends of the horizontal portion 25 and abutting against the inner sides of the opposite sheet-metal side walls of the body proper. The bridge 24, embodying the horizontal portion 25 and the end legs 26, essentially consists of a sheet-metal strip or plate provided at its upper edge with a horizontally-disposed rest-flange 25, constituting a part of the seat - support, and at its lower edge where an angle-iron is indispensable to get the proper trussing effect a reinforcing angle-iron strip 28 is secured to and along such edge through the medium of a series of securing-rivets 29. In this construction the angle-iron strip 28 has the vertical flange thereof secured to the outer side of the bridge proper, 24, through the medium of the securing-rivets 29, while the horizontal flange of said strip projects beneath the lower edge of the bridge in parallelism to the upper rest-flange 25 thereof. It will be observed that in attaching the angle-iron strip 28 to the bridge-plate the heads of the rivets are upset against the rigid angle-iron on the side exposed to view, but under such conditions will not work loose and show breaks in the finished surface of the body.

In a vehicle of the form illustrated in Fig. 1 of the drawings the side of the vehicle-body between the front and rear seats is formed with a door-opening 30, within which is arranged to work a swinging door 31, hinged at one edge, as at 32, to one side of the opening through the medium of any suitable type of hinges. The door or door-opening is of any desired configuration according to the variations in design of the vehicle-body, but in all instances preserves the improvements adapted thereto. To carry out the general sheet-metal formation of the vehicle - body, the door proper, 31, is constructed of one or more sheet-metal plates provided at the marginal or border edges with inturned stiffening-flanges 33, inside of which may be arranged the wooden or equivalent stiffening-frame 34, secured to said flanges by means of screws or equivalent fasteners 35, thus providing the reinforce - flange construction which is involved in the general body formation. The said swinging door 31, constructed as described, is designed to be equipped with a

suitable latch or lock and has fitted to the free edge thereof a stop-strip 36. This stop-strip 36 is preferably of a T shape, having the web 37 thereof secured against the free edge of the door by means of the fasteners 38 and having its cross - head arranged at the outer side of the door to present a stop-shoulder 39, adapted to overlap and abut against the edge of the door-jamb when the door is closed. In connection with the stop-strip 36, carried by the free edge of the door, it will be observed that the door-jamb for said free edge of the door is preferably formed by the front edge of the rear seat-body, which front edge is provided with the inturned marginal stiffening-flange 21, previously referred to. To effect a proper reinforcement of this flange to constitute a door-jamb, there is riveted to the same by means of the rivets 40 an angle-iron door-jamb reinforce-strip 41, which is arranged over the edge of the said flange 21, so as to dispose one flange of the strip 41 on the outside of the flange 21 and bring the said flange of the strip 41 flush with the outer face or side of the sheet-metal seat body-plate, so that such flange will receive the impact or shock incident to the closing movement of the door and prevent the stop-strip 36 from hammering onto and indenting the sheet-metal plate. It will be observed that the door-jamb reinforce-strip 41 extends down to the seat-frame 23 of the rear seat and is formed with a horizontal bracing extension 42, which fits over and is secured to the front edge of the seat-frame, thereby affording a brace for the body portion of the seat to brace the same against the shock incident to the closing of the door.

An obvious modification of the construction just described resides in arranging a door-jamb reinforce angle-iron strip 41^a within the angle formed by the flange 21 at the front edge of the rear seat-body, as plainly shown in Fig. 4 of the drawings; but this construction is not so desirable, for the reason that it leaves the outer side of the sheet-metal plate exposed to the hammering of the door - stop. To provide for giving proper finish to the door-opening, the same has arranged about the edge thereof upon the outer side of the body a wooden molding-piece 43, which molding-piece extends up the corners of the body, forming the rear side of the front seat. Also the door-sill or threshold is covered with a threshold-strip 44, of brass, to relieve the thin inturned metal of the body at this point and prevent its being broken down, thus distorting the turned-in flange of the sill. This is of course important where a side door is employed.

Another detail of the invention resides in employing angled top - supporting brackets 45. These brackets are so arranged that their horizontal portions pierce through the metal seat-bodies near the edges thereof, 130

while the vertical legs 46 are disposed along the inner sides of such bodies and rigidly secured thereto by means of the fastenings 47, said legs being also provided at their lower ends with inturned feet 48, secured to the seat-frames. This provides an exceptionally-rigid bracing for said top-supporting brackets in connection with the metal plates of the body and seat structure.

10 From the foregoing it is thought that the essential features and advantages of the invention will be readily apparent without further description, and it will be understood that various changes in the form, proportion, 15 and minor details of construction may be resorted to without sacrificing any of the advantages of the invention.

What we claim, and desire to secure by Letters Patent, is—

20 1. A metal vehicle - body having body-forming plates provided at their marginal borders with integral stiffening-flanges and reinforce-beads contiguous to such flanges.

25 2. A metal vehicle - body having body-forming plates provided at their marginal borders with continuous integral inturned stiffening-flanges and outwardly-convexed reinforce-beads contiguous to and following said flanges.

30 3. A metal vehicle - body having body-forming plates provided at their marginal borders with continuous inturned stiffening-flanges, and concavo-convex beads formed therein in contiguous relation to said flanges.

35 4. A metal vehicle - body having a body proper and seats constructed of metal plates provided at their marginal borders with continuous inturned stiffening-flanges and outwardly-convexed reinforce-beads formed in 40 the plates in contiguous relation to said flanges.

45 5. A metal vehicle - body having body-forming plates provided at their marginal borders with inturned stiffening-flanges and reinforce-beads disposed contiguous to and following the flanges, the body-plates and their flanges being united together and bearing an overlapping relation to the corner-joints.

50 6. A metal vehicle - body having body-forming plates provided at their marginal borders with inturned stiffening-flanges, said plates and their flanges being secured together and bearing an overlapping relation 55 at the corners of the body, and a corner-reinforcing plate arranged at one side of and secured to the overlapping flanges at the corners.

60 7. A metal vehicle - body having body-forming plates provided at their marginal borders with inturned stiffening-flanges and with concavo-convex reinforce-beads following the said flanges in contiguous relation thereto, said plates and their flanges being

secured together and bearing an overlapping 65 relation at the corners, and an extra convexed upright finishing-strip secured along the outer side of each rear corner of the body with its rounded surface merging into the corresponding surface of the adjacent upright concavo-convex reinforce-beads to produce an exteriorly-rounded corner-joint.

8. A metal vehicle - body having body-forming plates provided at their marginal borders with inturned stiffening-flanges, and 75 convex reinforce-beads arranged contiguous to and following said flanges, said body-plates and their flanges being secured together and bearing an overlapping relation at the corner-joints, and at such joints one of the body-plates and its flange being formed with a depressed seat or offset for the flanges of the other plate.

9. A metal vehicle-body having opposite 85 metal side walls each provided at their marginal borders with inturned stiffening-flanges, an inner upright filling - board arranged at the inner side of the said wall and secured at its upper edge to the upper flange thereof, a lower horizontal supporting-strip arranged 90 beneath the lower edge of the filling-board and secured to the lower flange of the sidewall, said strip being of a greater width than the board to provide a ledge or shelf and the flooring arranged for support on the ledge or 95 shelf of said strip.

10. In a vehicle - body, the combination with the body proper and the seat, of a transversely-arranged seat-support consisting of a transverse body member and a transversely-arranged metal bridge disposed beneath the frame and provided with an inturned flange at its upper edge.

11. In a vehicle - body, the combination with the body proper and the seat, of a seat-support consisting of a transverse body proper and a transversely - arranged metal bridge disposed along the front edge of the seat and provided at its upper edge with an inturned rest-flange and at its lower edge 110 with a reinforcing-strip.

12. In a metal vehicle-body, the combination with the metal body proper and the seat or seats, of a seat-support comprising a transverse body member and a transversely-arranged metallic bridge disposed beneath the edge of the seat-frame and consisting of a metal plate having a horizontal portion and terminal end legs, the latter disposed at the inner sides of the metal body, said bridge being provided at its upper edge with an inturned rest-flange and at its lower edge with a separate reinforcing angle-iron strip.

13. In a metal vehicle-body, the combination of the body proper provided with a door-opening and formed of plates provided at their marginal borders with inturned stiffening-flanges, and a door consisting of a metal

body or frame provided at the marginal borders thereof with an inturned stiffening-flange.

14. In a metal vehicle-body, the combination with the body proper having a door-opening and consisting of metal plates provided at their marginal borders with inturned stiffening-flanges, one of the flanged edges constituting a door-jamb, an angle-iron door-jamb reinforce-strip secured to the flanged edge constituting the jamb, and a flanged metal door carrying at its free edge a stop member.

15. In a metal vehicle-body, the combination of a body proper provided with a door-opening and consisting of plates provided at their marginal borders with stiffening-flanges, one of the flanged edges constituting a door-jamb, an angle-iron reinforce-strip fitted over the flanged edge constituting the door-jamb and presenting an abutment edge flush with the outer side of the plate, and a flanged metal door provided at its free edge with a T-shaped stop-strip coöperating with said angle-iron reinforce-strip of the jamb.

16. A metal vehicle-body provided with a door-opening and consisting of plates provided at their marginal borders with stiffen-

ing-flanges, one of the flanged edges constituting a door-jamb, a reinforcing angle-iron strip fitted over the said flanged edge forming the door-jamb and having a horizontal bracing extension secured to a member within the body, and a door arranged to cover said door-opening.

17. In a vehicle-body, the body proper having a door-opening and consisting of body-forming plates provided at their marginal borders with stiffening-flanges, a molding-piece extending about the edge of the door-opening at the outer side of the body, a metal threshold-strip secured to the molding-piece at the sill of the door-opening, and a metal door arranged to cover the door-opening.

18. In a vehicle-body, the combination with the metal body portion, of an angled top-supporting bracket piercing the metal body near an edge thereof and having a leg secured to the inner side of the metal body and formed at its lower end with the foot secured to a member within the body.
